FLOODLIGHT

Buell Moore, Houston, Tex., assignor to Esquire, Inc.,
New York, N.Y., a corporation of Delaware

Filed Apr. 10, 1969, Ser. No. 16,682

Term of patent 14 years

Int. Cl. D26—02

U.S. Cl. D48—20

FIG. 1

FIG. 3

FIG. 2

FIG. 4

FIG. 1 is a perspective view of a floodlight embodying my design, as seen from one corner and the bottom thereof;

FIG. 2 is another perspective view of the floodlight, as seen from the opposite corner and the top thereof;

FIG. 3 is a perspective view of the floodlight, when inverted top for bottom from the position of FIGS. 1 and 2, and as seen from one corner and the top thereof;

FIG. 4 is another perspective view of the floodlight in the position of FIG. 3, and as seen from the opposite corner and top thereof.

The support members are indicated in broken lines in FIGS. 1-4 for illustrative purposes only and form no part of the design.

I claim:

The ornamental design for a floodlight, substantially as shown and described.
